Inventor:

Richard Woodcock

United States Patent Office.

RICHARD WOODCOCK, OF JOLIET, ILLINOIS.

Letters Patent No. 62,914, dated March 12, 1867.

IMPROVED TILE AND PIPE MACHINE.

The Schedule referred to in these Letters Patent and making part of the same.

Be it known that I RICHARD WOODCOCK, of the town of Joliet, in Will county, and State of Illinois, have invented a new and useful improvement on a Tile and Pipe Machine; and I do hereby declare that the following is a full and exact description of the construction and operation of the same, reference being had to the annexed drawings, making a part of this specification, in which—

Figure 1 is a perspective view.

Figure 2, a longitudinal elevation; and

Figures 3 and 4, different views of the part called the receiver.

I construct the pug-mill *a* in a cylindrical form, placing the same in a horizontal position, furnished with a main shaft, *b*, with the ordinary blades and screws for working the clay and pressing it toward the aperture at one end; from whence issues the tile. The particular part of the mill that I call new, as distinguished from that which is old, is the self-revolving core shaft *c*, with the core *e* permanently attached thereto, and forming a part thereof, running through the entire length of the hollow main shaft *b*, as shown in fig. 2, by means of which the core *e* is held in its proper position without any possibility of its getting out of the centre of the aperture in the die plate *f*. The core shaft is held in its place in the main shaft by a nut, *g*, at the outer end, and, being loose in said shaft, revolves by the pressure of the clay as it passes from the mill around the core *e*, through the aperture in the centre of the die plate *f* with a spiral motion imparted by the screws of the main shaft, in consequence of which the core is less liable to tear the tile or pipe as it emerges from the machine than when it is made to revolve by other means. The core being attached to so long a shaft is effectually prevented from wobbling, and preserves a uniform thickness of the walls of the tile. For the purpose of receiving the tile or pipe from the mill I use the receiver *i*, (figs. 3 and 4, and fig. 1,) which consists of a concave or half cylinder, of a diameter and length to correspond with the required size of the tile or pipe. The concave is set in a bed or frame, as is shown in figs. 3 and 4, with guides at each corner for the purpose of guiding a wire to cut the tile or pipe off at the ends. In fig. 1 the receiver is shown as receiving a tile from the machine. The receiver rests when receiving the tile or pipe in the frame *m*, (fig. 1,) on the row of rollers *n*, so that after it has received the tile or pipe it may slide away from the mill to give place to another receiver for the next tile or pipe. The receiver is also used to carry the tile or pipe from the mill, and for turning them on end, while in the green state, to dry, as shown in fig. 4.

Claim.

What I claim as my invention, and desire to secure by Letters Patent, is—

1. The self-revolving core shaft *c* in the hollow main shaft *b*.
2. The receiver *i*, answering the double purpose of receiving the tile from the mill and handling the same while in a green state.
3. A combination of the self-revolving core shaft *c*, the main shaft *b*, and the receiver *i*, when used and operating substantially as described.

RICHARD WOODCOCK.
